Specification of Letters Patent.

Patented Oct. 7, 1913.

Application filed November 19, 1910. Serial No. 593,213.

To all whom it may concern:

Be it known that we, JOHN A. WERNER and CHARLES W. GREEN, citizens of the United States, residing at Dayton, in the county of Montgomery and State of Ohio, have invented certain new and useful Improvements in Multiple Cash-Registers, of which we declare the following to be a full, clear, and exact description.

10 This invention relates to multiple totalizer cash registers and among the objects of the invention are to provide an improved differential mechanism for accounting machines comprising an extremely simple construction without springs, for converting an invariable movement into any desired differential movement.

Another object of the invention is to provide an adjustable differential mechanism 20 which, after operation, is automatically returned to its adjusted position in condition to repeat the same operation without readjustment.

Another object of the invention is to provide a lever set cash register having a plurality of totalizers with an improved differential mechanism for operating the totalizers.

With these and incidental objects in view, 30 the invention consists in certain novel features of construction and combinations of parts, the essential elements of which are set forth in appended claims, and a preferred form of embodiment of which is 35 hereinafter described with reference to the drawings which accompany and form part of the specification.

Of said drawings: Figure 1 is a transverse vertical section of a cash register constructed according to this invention and including part of an improved differential mechanism. Fig. 2 is a detail in side elevation of a counter operating pitman, also shown in broken lines in Fig. 1. Fig. 3 is a detail in side elevation of a differential mechanism and its driving connection to the main drive shaft of the machine. Fig. 4 is a detail of part of the differential mechanism shown in Fig. 3. Fig. 5 is a left side elevation of 45 the machine and showing particularly the construction of the multiple totalizers and the main driving mechanism. Fig. 6 is a left side elevation of the machine with the multiple totalizers and driving connections

omitted in order better to show the construction of the multiple totalizer setting lever and its connections to the transaction indicator mechanism, and a machine locking device temporarily actuated by the lever to lock the machine while the lever is being set. Fig. 7 is a top plan view of the differential mechanism for actuating the multiple totalizers.

The invention as herein described is embodied in a lever set multiple totalizer cash register and is shown as applied to the single totalizer machine fully described and shown in the United States Patent to Thomas Carroll No. 751,611. The patent shows a machine having a plurality of differentially movable segmental setting levers provided with teeth meshing with pinions rigidly connected to type carriers. Individual items are therefore set in the type carriers according to differential movement of the levers. The levers also mesh with racks having teeth, more or less of which, by movement of the levers, are set in the path of a movable totalizing device, for the purpose of causing the totalizing device to be 80 differentially rotated as desired when moved over the racks.

In the application of the present invention the setting levers, printing mechanism and movable totalizer are retained, and in addition a plurality of special transaction totalizers are provided. Any one of the transaction totalizers may be indirectly actuated through the medium of the racks above referred to. For this purpose the 90 racks are provided with an additional set of teeth meshing with pinions connected to actuating segments for the multiple totalizers.

The multiple totalizers are carried by a 95 rotatable reel having a geared connection to a setting lever by which the reel may be differentially rotated for the purpose of positioning a desired totalizer opposite the actuating segments. The construction of the 100 totalizer reel, the totalizers carried thereby and suitable carrying mechanism for the totalizers is substantially shown and described in the United States Patent to Thomas Carroll No. 703,639.

105 The driving mechanism of the machine is adapted to move the main totalizer over the racks and to mesh the selected one of the

multiple totalizers with the actuating segment gears, and then to restore the segments to the normal zero position from which they were moved by the setting levers. The return movement of the segments effects the desired rotation of the totalizer elements.

The present invention relates principally to the differential mechanism employed for actuating the multiple totalizers. This differential mechanism includes a novel connection between the aforesaid pinions, meshing with the racks, and the totalizer actuating segment gears, whereby on the restoring movement of the segments, the pinions, racks, and setting levers are not disturbed, but after the totalizer is actuated it is moved out of mesh, and the segments are returned to the position to which they were set by the setting levers. By this arrangement it is possible to repeat the same operation as often as desired without requiring readjustment of the setting levers. The particular means employed to effect the above object will be fully described with reference to the drawings.

Driving mechanism.—The drawings show a manually operated driving mechanism consisting of a crank 80 (Fig. 5) rigid with a pinion 81 and journaled on a stub shaft 82. The crank is geared to the main drive shaft 59 by the pinion 81 meshing with an intermediate gear 83, in turn meshing with a pinion 84 fast to a pinion 85 meshing with a pinion 86 fast to the main drive shaft. The gearing is such that two rotations of the crank 80 are required to effect one rotation of drive shaft 59.

Setting elements.—The controlling mechanism for the machine is positioned by a plurality of value setting levers 1 (Fig. 1) and a special totalizer reel setting lever 2 (Figs. 5 and 6). The setting levers 1 are each provided with rack teeth 3 meshing with pinions 4 fast to a shaft 5 and to sleeves 6 surrounding shaft 5. On this shaft and the sleeves are rigidly mounted value type wheels 7, therefore adjustment of the setting levers 1 sets the type wheels in correspondence. The type wheels are provided with two sets of characters so that double impressions may be taken of amounts determined by the setting of levers 1. The impression mechanism is omitted from the drawings but is described in the aforesaid patent to Carroll No. 751,611.

For the purpose of setting main racks 8, which serve to communicate movement of the levers 1 to the accounting mechanisms, the levers 1 are provided with a second set of rack teeth 9 meshing with teeth 10 in the racks 8. The racks 8 have teeth 11 meshing with pinions 12 fast to value indicators 13 thereby serving to rotate the indicators 13 according to the adjustment of the levers 1.

Secured to the racks 8 are main totalizer controlling racks 14, normally out of cooperative relation with a main or cash totalizer 15, and moved into operative relation with the same by adjustment of the levers 1. For communicating movement of the levers 1 to the operating mechanism for the multiple or reel totalizers, the racks 8 carry a set of rack teeth 16 meshing with pinions 17 loose on a supporting shaft 18 but rigid with notched disks 19. Pawls 20 pivoted to yokes 21 normally rest in notches 22 in the disks 19 and thus normally serve to communicate movement from the pinions 17 to the yokes 21. The yokes 21 (Fig. 7) are secured to sleeves 23 which carry rigidly multiple totalizer actuating segments 24. The pawls 20 are compelled to remain in engagement with the notches in disks 19 by circular arms 133 against which the pawls ride. Therefore movement of disks 19 by the hand levers 1, serves to move the pawls 20 and the actuating segments 24 differentially, but this hand operated movement is not employed to actuate the multiple totalizers as too much load would be thrown on the levers 1. To actuate the totalizers, the arms 133 are given an excursion of invariable extent at each operation of the main handle, around the shaft 18, and during this movement they pick up all the pawls 20 and return them to normal zero position, and then restore them to the previous differential setting.

Differential mechanism for the multiple totalizers.—After the totalizer is meshed with the segment gears 24 shaft 18 is oscillated by a segment gear 126 (Fig. 3) pivoted by a pin 127 to a fixed bracket 128 and provided with a roller 129 extending into a groove 130 in a disk 131 fast to drive shaft 59. The segment gear 126 meshes with a pinion 132 fast to shaft 18, and thus oscillation of the segment gear 126 by the groove 130 causes shaft 18 to be oscillated. The curved arms 133 are rigidly secured to shaft 18. When in normal position these arms 133 prevent pawls 20 from accidentally rocking out of engagement with the notches in disks 19. Oscillation of shaft 18 causes the arms 133 to be rocked far enough, in the direction of arrow 161, to carry any of the pawls 20 back to their normal position by engagement of shoulders 134 with the pawls. The shoulders 134 are so cut as to have a camming action when engaging the inclined edges 135 of the pawls for the purpose of rocking the pawls out of engagement with disks 19 and into engagement with notches 136 in the arms 133. By this means the pawls 20 are disconnected from disks 19 leaving the pinions 17, racks 8 and levers 1 in their adjusted position while the pawls are carried back to normal position, thus through the yokes 21 and segments 24, causing the desired differential rotation of the

selected totalizer on reel 31. During the return movement of pawls 20 disks 19 serve to prevent disengagement of the pawls from arms 133. Cam groove 130 is so formed that 5 pawls 20 are held in their normal positions for a time sufficient to permit unmeshing of the selected totalizer by returning the reel 31 to its lower position (Fig. 4) under the action of cam groove 124. After the unmeshing of the totalizer, shaft 18 is rocked back to normal position by the action of cam groove 130, thus causing all of the arms 133 to be carried to normal position, as shown in Fig. 3, and the pawls 20, yokes 21, and 10 totalizer actuators 24 to be restored to the position to which they were adjusted by levers 1. When the pawls 20 arrive at such adjusted positions their inclined edges 137 engage inclined shoulders 138 of disks 19, 15 and by such engagement are rocked into the notches 22 of the disks and so become disconnected from arms 133 which independently continue their movement to normal position.

20 By the above means the differential mechanism is restored to its set position and into operative relation with levers 1, therefore similar operations may be repeated without readjustment of levers 1, or the levers may 25 be adjusted to any other position without first being restored to zero position in order to effect a desired different operation of the machine.

Multiple totalizers.—The general arrangement of the multiple totalizers and the setting mechanism therefor has been pointed out. A selected totalizer is moved into mesh with segment gears 24 (Fig. 5) by bodily moving the reel 31 upward. For this purpose the shaft 110, which supports the reel, 30 is carried by slides 111. The slides are provided with flanges 112 and 113 fitting in channels 114 and 115 in brackets 116 and 117 secured to a side frame 118. One of the 35 slides 111 is provided with a pin 119 extending through a slot 120 in a bell crank lever 121, pivoted to the frame 118 by a pin 122 and having a roller 123 extending into a groove 124 in a disk 125 fast to the main 40 drive shaft 59. The groove 124 is so formed that the bell crank lever 121 will be rocked upwardly, thus meshing the selected totalizer 35 with the actuating racks 24, at the 45 beginning of rotation of shaft 59. The totalizer is held in mesh long enough to permit restoration of the actuators 24 to zero position, as described farther on.

The multiple totalizer reel setting lever 2 (Figs. 5 and 6) is secured to a short shaft 50, 25, to which is rigidly secured a segment gear 26 meshing with a segment gear 27 rigid on a shaft 28 with a forked arm 29. A rack 30 for rotating the transaction totalizer reel 31 meshes with a pinion 32 fast to 60 the reel and is slidably mounted on pins 33

and also carries a pin 34 passing through the fork in arm 29. This arrangement results in differential movement of the lever 2 being communicated to the totalizer reel 31 through the segments 26 and 27, arm 29 and rack 30, and thus any desired totalizer 70 35 on the reel may be positioned near the actuators 24.

In order that the operator may know when the lever 2 is properly adjusted so that the desired totalizer is opposite the actuators 24, the lever 2 carries a spring actuated plunger 36 co-acting with notches 37 in a segmental plate 38 rigidly secured by pins 39 to a machine side-frame 40. The plunger 36 is mounted on a short plate 41 hung by links 42 from pins 43 on the lever 2. The lever 2 carries a pin 44 on which is pivoted a thumb grip 45 having an arm 46 for engaging a lug 47 of the plate 41. By forcing the thumb grip 45 toward lever 2 the arm 46 pushes plate 41 inwardly thereby carrying plunger 36 out of one of the notches 37 and thus permits setting movement of lever 2. The plunger 36 has a shoulder 48 extending across the front edge 49 of a curved plate 50 pivoted by pins 51 to a pair of arms 52, pivoted on the machine frame by pins 39 and pivoted together by a pin 53 carried by one of the arms and passing through a slot in the other. A pin 54 on the lower arm 52 passes through a fork in a bell crank lever 55 pivoted to the frame 40 by a pin 56 and provided at its rear end with a locking nose 57 co-acting with a notched disk 58 fast to the main drive shaft 59 of the machine. A spring 60 is extended between a pin 61 on frame 40 and a pin 62 on bell crank lever 55 and normally serves to hold the bell crank lever, the arms 52, plate 100 50, plunger 36 and thumb grip 45 in the position in which they are shown in Fig. 6. When the thumb grip is depressed shoulder 105 48 of plunger 36 forces plate 50 rearwardly thereby rocking the arms 52 rearwardly and thus, through the pin 54, operating bell crank lever 55 to carry its nose 57 into the notch in disk 58. The machine is thus locked against operation while lever 2 is being adjusted from one position to another, 110 as it is impossible to adjust lever 2 without depressing thumb grip 45 and bell crank lever 55 cannot return to its unlocking position until the thumb grip is released, permitting plunger 36 to enter one of the notches 37. If the lever 2 is set to a position such that the plunger 36 is between two of the notches 37, no totalizer will be opposite actuators 24 and plate 38 serves to hold the plunger 36 in its inner position and consequently the bell crank lever 55 in its locking position.

Main totalizer.—The main totalizer 15 (Fig. 1) is identical in construction with that shown and described in the aforesaid 130

patent to Carroll, No. 751,611, and will be but briefly described. This totalizer consists of a plurality of pinions 87 loosely journaled on a shaft 88 journaled in a frame 89. The totalizer carrying frame 89 is provided with rollers fitting in channels 90 in a frame 91 hung from a rod 92 carried by ears 93 on a tie bar 94. The frame 89 is normally supported in its upper position, as shown in Fig. 1, by pitmen 95, pivoted at their rear ends on a rod 96 supported in brackets 97, and at their forward ends provided with slots 98 through which a tie bar 99 of the totalizer frame extends. The pitmen 95 are provided with rollers 100 extending into cam grooves 101 in disks 102 fast to the drive shaft 59. The grooves 101 are so formed that upon rotation of drive shaft 59, the pitmen 95 are rocked downwardly around the rod 96 thereby causing the totalizer frame 89 to be moved downwardly. The totalizer remains at rest in its lowered position for a short time, after which the grooves 101 return the pitmen 95 to normal position thereby returning the totalizer 89 to normal position. During the downward movement of frame 89 the totalizer pinions 87 engage and are rotated by such of the racks 14 as have been moved upwardly by adjustment of levers 1, but in order not to rotate the totalizer upon the return movement of frame 89 the frame 91 is pivotally connected to pitmen 103 reciprocated by cam grooves 104 in disks 102. The grooves 104 are so formed as to rock the frame 91 rearwardly around the pivot 92 before the downward movement of the totalizer, thus bringing the totalizer pinions 87 into coöperative relation with racks 14 so that the same will be rotated when the totalizer is moved downwardly. When the totalizer is at rest in its lower position the frame 91 is returned to normal position thus permitting the totalizer to be returned to normal position without being reversely rotated by racks 14. During the return of the totalizer carrying operations occur if necessary, the means employed being fixed cams 105 acting upon rollers 106 of levers 107 which carry the transfer pawls 108. The transfer pawls 108 are in turn controlled to be effective or not by the totalizer pinions through the medium of trip pawls 109.

Multiple counters.—In order to count the number of times the different totalizers of the reel are actuated, a plurality of counters 139, (Fig. 1) one for each totalizer of the reel, are mounted on a rod 140 carried by brackets 141 secured to the frame of the machine. The pawls 142, for actuating the counters, are pivoted to levers 143 journaled on a rod 144 and having extensions 145 co-acting with oscillating arms 146. The arms 146 are fixed to a shaft 147, journaled in the side frames of the machine and

provided with a second arm 148, extending into a notch 149 in a pitman 150 (Fig. 2) actuated by a cam 151 fast on shaft 59. Upward movement of the pitman 150 causes the arms 146 to be rocked downwardly when one of them will engage one of the levers 143. The particular lever which it engages is determined by the setting of the class of transaction lever 2 for which purpose the transaction lever is rigid with a segment gear 152 (Fig. 1) meshing with a segment gear 153 fast to a shaft 154 carrying rigidly a bevel gear 155 meshing with a bevel gear 156 fast to a short shaft 157. The shaft 157 is journaled in a bracket 158 and carries rigidly a segment gear 159 meshing with curved rack teeth 160 carried by shaft 147. By the above arrangement longitudinal movement of shaft 147 is effected to position the arms 146 above the levers 143. The rack teeth 160 are curved so that shaft 147 can be oscillated without disconnecting the rack 160 from segment gear 159. It will be readily understood that the arms 146 are spaced, in accordance with the construction in Patent 703,639, at distances such that only one of them may engage a lever 143 at a time.

A special transaction indicator 63 is set by lever 2 through a segment gear 64 fast to shaft 25 and meshing with a rack 65 slidably mounted on pins 66 and meshing with a pinion 67 fast to the special indicator. This indicator is alined in its set position by a spring pressed pawl 68 co-acting with a notched alining disk 69 fast to the indicator.

A special transaction type carrier 70 is set by the lever 2 through a segment gear 71 fast to shaft 25 and meshing with a segment gear 72 fast to a shaft 73, which has rigidly secured thereto a segment gear 74 meshing with a rack 75 provided with teeth 76 meshing with a pinion 77 fast to the transaction type carrier 70. The rack 75 is guided in a vertical direction by pins 78 and 79.

Operation.—To enter a transaction in the machine, levers 1 are adjusted according to the amount of the transaction and lever 2 is adjusted according to the class of transaction thereby rotating reel 31 to position the desired transaction totalizer 35 opposite actuators 24. The levers 1 through rack teeth 3 set the type carriers 7 and through rack teeth 9 set racks 8 and through the racks 8 rotate the value indicators 13 to the desired positions and also the pinions 17, and through these pinions, disks 19 fast thereto, pawls 20, and yokes 21, differentially set the transaction totalizer actuators 24. The lever 2 sets the reel 31 through the segment gear 26, (Fig. 5) fast to lever 2 and meshing with segment gear 27, to which is secured arm 29 for reciprocating rack 30

5 this rack meshing with the pinion 32 fast to the reel 31. Lever 2 also sets the transaction indicator 63 (Fig. 6) through the segment gear 64 meshing with rack 65 which in turn meshes with the pinion 67 fast to the transaction indicator. The transaction type carrier 70 is set through the medium of segment gears 71, 72 and 74, rack 75 and pinion 77. After the levers 1 and 2 are 10 adjusted as desired, crank 80 (Fig. 5) is twice rotated thus causing one rotation of shaft 59. This shaft, through the cam disk 125, oscillates bell crank lever 121, thereby meshing the selected special totalizer with the actuators 24, and after the totalizer is 15 meshed, through the cam disk 131 (Fig. 3) oscillates segment gear 126 thereby oscillating shaft 18 and the curved arms 133. When notches 136 in the curved arms arrive opposite the ends of pawls 20 in whatever position the pawls have been adjusted to, shoulders 134 of the arms cam the pawls out of engagement with disks 19 and into engagement with the notches 136. During the further movement of arms 133 the pawls are 20 carried back to their normal positions, thereby returning the actuators 24 to their normal positions, and differentially rotating the selected totalizer as desired. While the 25 actuators 24 are at rest in their normal positions cam disk 125 (Fig. 5) disengages the transaction totalizer from actuators 24 after which segment 126 (Fig. 3) is restored to normal position thus returning the curved arms 133 to normal position. During the 30 return of curved arms 133, when pawls 20 arrive opposite notches 22 in disks 19, shoulders 138 of the disks engage the inclined edges 137 of the pawls, thereby rocking the 35 pawls out of engagement with the arms 133 and into engagement with the notches 22 in disks 19, thus leaving the pawls in the position to which they were adjusted by levers 1. During the operation of the selected 40 transaction totalizer the main totalizer 15 is actuated to a similar extent by its reciprocation over racks 14 under the action of pitmen 95 (Fig. 1).

As before stated, the invention relates 45 mainly to the differential mechanism for actuating the multiple totalizers, and it is not desired to claim the invention shown in the drawings, merely in connection with the patented machine.

55 While the form of mechanism herein shown and described is admirably adapted to fulfil the objects primarily stated it is to be understood that it is not intended to confine the invention to the one form of embodiment herein shown and described as it is susceptible of embodiment in various forms all coming within the scope of the claims which follow.

What is claimed is:

60 1. In a machine of the class described, the

combination with an accounting device, of differential mechanism for actuating the accounting device, said differential mechanism including; a segment gear, a pawl rigidly connected with the segment gear and 70 having two oppositely extending teeth, a differentially movable member normally in engagement with one of said teeth for the purpose of differentially setting the segment gear, and a curved plate having a notch and 75 positioned to prevent the pawl from becoming disengaged from said differentially movable member; and means for oscillating said plate an invariable extent thereby causing the pawl to enter said notch and move with 80 the plate to its original position and back again.

2. In a machine of the class described, the combination with an accounting device, of a differentially movable setting lever, a 85 notched disk suitably connected to said lever to be rotated by the lever, an accounting device actuator, a pawl connected to the actuator and positioned to be engaged by the notched disk for the purpose of differentially setting the accounting device actuator, a member constructed to disconnect said pawl from the disk and connect the pawl with itself and then to restore the pawl and the actuator to their original position, and 90 means for moving said member invariable extents.

3. In a machine of the class described, the combination with an accounting device, of a differentially movable setting lever, a 100 notched disk suitably connected to the lever to be rotated by the lever, an accounting device actuator, a pawl connected to the actuator and positioned to be engaged by the notched disk for the purpose of differentially setting the accounting device actuator, a member constructed to disconnect said pawl from the disk and connect the pawl with itself and then to restore the pawl and actuator to their original position and back 105 to the position to which they were moved by the lever, and means for moving said member.

4. In a machine of the class described, the combination with an accounting device, of a 115 differentially movable setting lever, a notched disk suitably connected to the lever to be rotated by the lever, an accounting device actuator, a pawl connected to the actuator and positioned to be engaged by the 120 notched disk for the purpose of differentially setting the accounting device actuator, a member constructed to disconnect said pawl from the disk and to connect the pawl with itself, and then restore the pawl and actuator to their original position and back 125 to the position to which they were moved by the lever, and finally to reconnect the pawl with the notched disk, and means for moving said member.

5. In a machine of the class described, the combination with an accounting device, an actuator therefor, two notched members, a pawl connected to the actuator and located 5 between the two notched members, means for moving each of said members, said pawl and said notches being so formed that movement of either one of said notched members will move the pawl and thereby move the ac- 10 counting device actuator.

6. In a machine of the class described, the combination with an accounting device, of an actuator therefor, two movable members, a pawl located between the movable 15 members and connected to the actuator, said pawl and movable members constructed so that one of said members normally engages the pawl whereby movement of said member will cause a corresponding movement of the 20 pawl and actuator and movement of the other member will cause the pawl to be disconnected from said first member and connected to said second member.

7. In a machine of the class described, the combination with an accounting device, of an actuator for the accounting device, two movable members, a pawl connected to the actuator and located between the movable members, means for moving one of said 30 members differentially, means for moving the other of said members an invariable extent, said members being so constructed that the pawl is compelled to engage either one or the other of said members, and that movement of either of said members will cause movement of the pawl with said member.

8. In a machine of the class described, the combination with an accounting device, of an actuator for the accounting device, two 40 movable members, a pawl connected to the actuator and located between the movable members, each of said members being provided with a shoulder and a notch at the side of the shoulder whereby movement of either 45 of said members may cause the pawl to be connected to said member and moved therewith.

9. In a machine of the class described, the combination with an accounting device, of an actuator for the accounting device, two 50 movable members, a pawl connected to the actuator and located between the movable members, each of said members being provided with a shoulder and a notch at the 55 side of the shoulder whereby movement of either of said members may cause the pawl to be connected to said member and moved therewith, means for moving one of said members differentially and means for moving the other of said members an invariable extent.

10. In a machine of the class described, the combination with an accounting device, of a differentially movable actuator for the 60 accounting device, two movable members, a

pawl connected to the actuator and located between the movable members, and means whereby movement of either of said members will cause movement of the pawl with said member.

11. In a machine of the class described, the combination with an accounting device, of an actuator for the accounting device, two relatively movable members, a pawl connected to the actuator and located between the movable members, said members and the pawl being constructed so that relative movement of said members effects differential movement of the pawl and the actuator.

12. In a machine of the class described, the combination with an accounting device, of an actuator for the accounting device, two relatively movable members, a pawl connected to the actuator and located between the movable members, said members and the pawl being so constructed that relative movement of said members effects differential movement of the pawl and the actuator, means for moving one of the said members differentially, and means for moving the other of said members an invariable extent.

13. In a machine of the class described, the combination with an accounting device, of an actuator for the accounting device, two relatively movable members, a pawl connected to the actuator and located between the movable members, said members suitably constructed to engage and move the pawl and thereby the accounting device actuator oppositely.

14. In a machine of the class described, the combination with an accounting device, of an actuator for the accounting device, two relatively movable members, a pawl connected to the actuator and located between the movable members, said members being suitably constructed to engage and move the pawl and thereby the accounting device actuator oppositely, and means for moving either of said members.

15. In a machine of the class described, the combination with an accounting device, of an actuator for the accounting device, two relatively movable members, a pawl connected to the actuator and located between the movable members, said members being suitably constructed to engage and move the pawl and thereby the accounting device actuator oppositely, and means for moving both of said members.

16. In a machine of the class described, the combination with an accounting device, of an actuator for the accounting device, two relatively movable members, a pawl connected to the actuator, said members being suitably constructed to engage and move the pawl and thereby the accounting device actuator oppositely.

17. In a machine of the class described, the combination with an accounting device,

of an actuator for the accounting device, two relatively movable members, a pawl connected to the actuator, said members being suitably constructed to engage and move the pawl and thereby the accounting device actuator oppositely, and means for moving either of said members.

18. In a machine of the class described, the combination with an accounting device, of an actuator for the accounting device, two relatively movable members, a pawl connected to the actuator, said members being suitably constructed to engage and move the pawl and thereby the accounting device actuator oppositely, and means for moving both of said members.

19. In a machine of the class described, the combination with an accounting device, of an actuator for the accounting device, two relatively movable members, a pawl connected to the actuator, said members being suitably constructed to engage and move the pawl and thereby the accounting device actuator oppositely, means for moving one of said members differentially, and means for moving the other of said members an invariable distance.

20. In a machine of the class described, the combination with an accounting device, of an actuator therefor, a member normally operatively connected with the actuator and adapted to be moved to position it differentially, and a second member adapted to pick up the differentially positioned actuator, disconnect it from the first member and restore it to zero position; the second member and the actuator being finally restored to the positions they occupied before the actuation of the second member.

40 21. In a machine of the class described, the combination with an accounting device, of a differentially movable actuator for the accounting device, two movable members, a pawl carried by the actuator and located between the movable members, and means whereby movement of either of said members will cause differential movement of the pawl with said member.

22. In a machine of the class described, the combination with an accounting device, of an actuator for the accounting device, two relatively movable members, a pawl carried by the actuator and located between the movable members, said members and

the pawl being constructed so that relative movement of said members effects differential movement of the pawl and the actuator.

23. In a machine of the class described, the combination with an accounting device, of an actuator therefor and two movable members adapted to be alternately connected with the actuator one for differentially adjusting the actuator and the other for moving it from its adjusted position to zero and back again, the connections between the actuator and the movable members being such that when the actuator is being moved by either of the movable members the other movable member locks it in operative engagement with the movable member which is actuating it.

24. In a machine of the class described, the combination with an accounting device, of an actuator for the accounting device, two movable members, a pawl connected to the actuator and located between the movable members, and means whereby movement of either of said members will cause movement of the actuator through said pawl.

25. In a machine of the class described, the combination with an accounting device, of an actuator for the accounting device, two movable members, a pawl connected to the actuator and located between the movable members, means whereby movement of either of said members will cause movement of the pawl with said member, and manipulative means for controlling the movement of the actuator by the movable members.

26. In a machine of the class described, the combination of a driving member having an invariable movement; a member adapted to be driven thereby; and means for positioning said member for controlling the movement imparted to it by the driving member, the construction of the members and means being such that the driving member and the means each lock the member with the other when the member is being actuated by such other.

In testimony whereof we affix our signatures in the present of two witnesses.

JOHN A. WERNER.
